ALARM SIGNAL SYSTEM

Clark Pool and Hugo F. Cypser, Brooklyn, N. Y.,
assignors to Signal Engineering & Manufacturing Company, New York, N. Y., a corporation of Massachusetts

Application May 18, 1938, Serial No. 208,614

6 Claims. (Cl. 177—369)

The present invention relates to alarm signal systems, particularly interior fire alarm systems, commonly installed in schools, factories, hotels and other large buildings, and employing a number of bells or other signals adapted to be sounded, or otherwise operated, in response to the actuation of any one of a number of alarm sending stations.

When installing an interior alarm signal system of the above indicated character, it is frequently necessary to provide a connection with a street fire alarm box of a city system, so that the city box will be tripped automatically, upon actuating any sending station of the interior fire alarm system. But such a city box connection should only be operative to signify the occurrence of a fire in the building protected by the interior alarm system, it being highly undesirable to have a city box tripped, upon the occurrence of a fault in the interior system, or should it be desired to operate the interior system for the purpose of holding a fire drill.

According to the present invention, there is provided an interior fire alarm system, including a connection with a city fire alarm box, so arranged as to prevent the city box from being tripped, upon the occurrence of a fault in the system, or should it be desired to operate the signals of the system for purposes of a fire drill. Therefore, the associated street fire alarm box will be tripped, and the city fire apparatus called, only when a station of the interior fire alarm system is operated for the sole purpose of giving an alarm of fire, as by breaking the glass, opening the door and pulling the usual handle or hook which sets the code dispatching mechanism into operation. Furthermore, provision is made to insure rewinding of a tripped city box by requiring manual resetting of the relay device which controls tripping of the city box, before the interior fire alarm system can be restored to a condition of complete supervision, following the sending of an alarm. The above and other advantageous features of the invention will hereinafter more fully appear from the following description, considered in connection with the accompanying drawings, in which:

Fig. 1 is a schematic wiring diagram of an alarm signal system embodying the invention, with the system in its normal condition of complete supervision.

Fig. 2 is a diagram similar to Fig. 1, illustrating operation of a city box trip coil, in response to actuation of a sending station of the interior alarm system.

5 Fig. 3 is a diagram, illustrating operation of the interior alarm system, without affecting the trip coil of the city box.

Fig. 4 is a view in side elevation of the trip coil relay.

10 Fig. 5 illustrates a mounting for the trip coil relay.

Fig. 6 is a view in side elevation of the dispatching mechanism of a sending station of the interior alarm system.

15 Fig. 7 is a view in end elevation of the parts shown in Fig. 6, as viewed from the left.

Fig. 8 is a view similar to Fig. 6, illustrating the manner of operating the dispatching mechanism, without energizing the trip coil of the city box.

20 Fig. 9 is a front view of the station box, on a reduced scale.

Like reference characters refer to like parts in the different figures.

Referring first to Fig. 1, the system comprises a main contactor relay A, providing an energizing winding 1 having one terminal thereof connected at a junction 2 to one of a pair of supply mains 3 and 4, energized from a suitable source of electrical energy. The other terminal of the relay winding 1 is connected to the movable arm 5 of a station control relay B having an energizing winding 6, also connected to the junction point 2 leading to the supply main 3. With the winding 6 energized, as shown, the arm 5 is maintained in engagement with a stationary contact 7, and this contact 7 is connected to the stationary contact 8 of a city box control relay C. The relay C provides a winding 9 having one terminal connected to the junction point 2, and with the winding 9 energized, one movable arm 10 of the relay C is maintained in engagement with the contact 8.

45 The arm 10 of the relay C is connected to one terminal of the winding 11 of a supervisory relay D, the other terminal of which is connected in series with the operating windings 12 and balancing resistors 12a of a number of alarm signals 13, indicated as being of the single stroke 50 plunger type. The winding 12 of the last signal section is connected to the signal winding 14 of a trip coil relay E, with the other terminal of the winding 14 connected to one of a pair of normally closed latch controlled contacts 15, the purpose of which will be hereinafter referred to.

The other contact 15 is connected in series with balancing resistor 16 for relay E and signal circuit protective resistor 17, to the other supply main 4.

One terminal of the winding 6 of the station control relay B is connected to the junction point 2 leading to supply main 3, and the other terminal of this winding is connected in series with pairs of normally closed coding contacts 18 of a number of alarm sending stations S of the interior fire alarm system. Each pair of station contacts 18 cooperates with the code wheel 19 of a dispatching mechanism, hereinafter described, and as long as the station S remains in a non-operating condition, the coding contacts 18 remain closed. The contact 18 of the last station of the system is connected to the supply main 4, through a station protective resistor 20.

The winding 9 of the city box control relay C, with one terminal connected to the junction point 2, has its other terminal connected in series with pairs of normally closed contacts 21, forming part of the dispatching mechanism of each station S. The contacts 21 are maintained in engagement by a cam device 22, forming part of the dispatching mechanism of a station S, and there will be hereinafter described an arrangement whereby the contacts 21 can only be opened when a station S is actuated for the purpose of sending a fire alarm. The contacts 21 of the last station S are connected to the supply main 4 through a protective resistor 23.

As previously pointed out, the system of the present invention provides an arrangement whereby the fire alarm box of a city system may be tripped and a portion of such a street box is indicated at 24 as providing a trip coil 25, which, upon being energized, will release the dispatching mechanism of the box so as to transmit an alarm to the central station. The trip coil 25 is adapted to be energized from the supply mains 26 of the city system, but the coil 25 is normally shunted out of circuit by conductors 27 leading to the trip coil relay E. The conductors 27 are connected to a pair of normally closed contacts 28, and these contacts 28 are in turn connected in parallel with a stationary contact 29 normally engaged by a movable arm 30 of the relay E. The purpose of the parallel connected contacts 28 and contact 29 with arm 30, will hereinafter more fully appear, and it is sufficient to state at this point, that the city box trip coil 25 cannot be energized until the winding 14 of the trip coil relay E has been fully energized, so as to separate contacts 28 and to move arm 30 out of engagement with stationary contact 29.

All of the current carrying elements entering into the system described thus far are under continuous electrical supervision, and there are three supervisory circuits, which may be conveniently traced, starting from the main 4. The signal and main contactor supervisory circuit includes the resistors 17 and 16, from which the current flows through the normally closed contacts 15, and the winding 14 of the trip coil relay, and then through the windings 12 and balancing resistors 12a of the several sections of signals. From the signals 13, the supervisory current traverses the winding 11 of the supervisory relay D, the normally engaged arm 10 and contact 8 of the city box control relay C, contact 7 and arm 5 of the station control relay B, and finally the winding 1 of the contactor A, which is connected to the junction point 2 leading to

the grounded supply main 3. The value of this supervisory current is not sufficient to energize either the winding 1 of the contactor A, signal windings 12, or the winding 14 of the trip coil relay E, although it is sufficient to energize the winding 11 of the supervisory relay D, and so maintain one arm 31 of this relay out of engagement with a stationary contact 32.

The arm 31 is connected to one terminal of the winding 33 of a trouble signal 34 of any desired type, with the other terminal of winding 33 connected to one side of a source 35 that is preferably independent of the source of electrical energy supplying the signal system mains 3 and 4. The other side of source 35 is connected to the contact 32 of the supervisory relay D, so that while the winding 11 remains energized, due to the flow of supervisory current therethrough, the trouble signal 34 remains silent. It is apparent, however, that a fault, such as a break or ground occurring in the supervisory circuit traced above, will result in energization of the trouble signal 34, to indicate the existence of the fault.

A second supervisory circuit for the sending stations S may be traced from the main 4, through the station resistor 20 and then through the normally closed pairs of contacts 18 of the sending stations S. The circuit extends from the stations through the winding 6 of the station control relay B to the junction point 2 leading to the grounded supply main 3. The value of this supervisory current is sufficient to energize the winding 6 and cause its arm 5 to be maintained in engagement with the stationary contact 7. Therefore, any fault in the circuits of the station contacts will result in the relay B dropping back, so as to break the main supervisory circuit at the contact 7 and cause deenergization of the supervisory relay winding 11, with resulting operation of the trouble signal 34.

A third supervisory circuit extends from the supply main 4 through the resistor 23 to the pairs of normally closed contacts 21 of the several stations, and then through the winding 9 of the city box control relay C to the junction point 2 leading to the grounded supply main 3. The value of this supervisory current is sufficient to energize the winding 9 and cause it to maintain the arm 10 in engagement with stationary contact 8 in the main supervisory circuit. Therefore, the occurrence of a fault in the circuits including the normally closed control contacts 21, will result in dropping back of the relay C to interrupt the main supervisory circuit at the contact 8 and cause energization of the trouble signal 34.

When a station S is actuated, for the purpose of giving an alarm, operation of its dispatching mechanism, hereinafter described, causes rotation of the code wheel 19, and the coding projections 19a on this wheel cause successive opening and closing of the associated station contacts 18 for a predetermined number of rounds. Upon the first opening of the contacts 18, the winding 6 of the station control relay B is de-energized, and the relay arm 5 drops, to engage a stationary contact 36, as shown in Fig. 2. This contact 36 is connected by a conductor 37 to the main 4 beyond the stations S, so that the main contactor winding 1 becomes fully energized, upon the first opening of the station contacts 18. Full energization of the winding 1 causes its movable contact arms 38 and 39 to engage spaced pairs of stationary contacts 40,

41 and 42, 43, respectively, thereby establishing operating circuits for the signals 13, as well as partially establishing an energizing circuit for the winding 14 of the trip coil relay E.

Upon bridging of the spaced stationary contacts 40 and 41 by the arm 38 of the contactor A, a circuit is established from the supply main 4, through conductors 44 and 45 to a junction point 46 between the windings 12 of the signals 13. From this point, the current divides and flows through the signal windings 12 and parallel conductors 47a and 47b to the then engaged contactor arm 39, contacts 42 and 43, and grounded supply main 3. This current flow is indicated by the arrows in Fig. 2, and it is obvious that successive opening and closing of the station contacts 18 will result in successive energizations of the signal windings 12, to cause a code to be sounded in accordance with the arrangement of the code projections 19a on the code wheel 19.

It is to be noted that the energizing circuit for the contactor winding 1 is such that a ground on a station circuit will not cause the signals 13 to sound, although a break will cause the signals to sound one stroke, coincidentally with operation of the trouble signal 34. Since the energizing current for winding 1 must pass through resistor 20, as indicated by arrows in Fig. 2, any ground on a station circuit will cause relay B to connect this ground to non-grounded terminal of winding 1.

As previously pointed out, the present invention contemplates the provision of an arrangement whereby the trip coil 25 of the city box 24 will be energized to operate the connected city box, in response to actuation of a station S to sound a fire alarm in the system. To this end, the dispatching mechanism of each station S, provides means whereby the cam device 22 will be operated to cause separation of the control contacts 21, immediately upon setting the dispatching mechanism in operation. The contacts 21 are shown disengaged in Fig. 2, from which it is evident that the circuit of winding 9 of the city control box relay will be interrupted. Upon deenergization of the winding 9, an arm 48 of the relay C will fall, to engage a contact 49, thereby establishing a circuit through conductor 50 from contact arm 38 of contactor A, which is then connected to supply main 4 through conductor 44. This circuit is continued from the arm 48 through conductor 51 to a stationary contact 52 of the supervisory relay D, which contact 52 is then engaged by an arm 53, due to the previous deenergization of the winding 11, upon breaking of the main supervisory circuit at the contact 7 of the station control relay B. Upon engagement of the contact 52 by the arm 53, a circuit is established through conductor 54 to a junction point 55 between the resistors 16 and 17, thereby cutting the resistance 17 out of circuit with the trip coil relay winding 14.

Since the other terminal of the trip coil winding 14 is connected by the conductor 47a to the contact 42 of the main contactor A, which contact is then connected to supply main 3, deenergization of city box control relay C with the contactor A energized, causes full energization of the winding 14, with resulting opening of the parallel pairs of contacts 28 and 29, 30. When this occurs, the shunt around the terminals of the trip coil 25 is removed, thereby causing energization of the coil 25 and tripping of the normally wound dispatching mechanism of the city

box to transmit an alarm to fire headquarters and so call the city fire apparatus.

From the foregoing description of the manner in which an energizing circuit for the winding 14 of the trip coil relay E is established, it is evident that the winding 14 can be energized only when deenergization of the relay C is accompanied by energization of the contactor A and deenergization of the supervisory relay D. Therefore, an accidental break, or ground, in either the city box control circuit, or the trip coil relay circuit, will not cause tripping of the city box 24, nor will failure of the source supplying the mains 3 and 4 have any effect on the city box.

As best shown in Fig. 4, the city trip coil relay E is so constructed that the possibility of the shunting contacts 28 and 29, 30 becoming accidentally disengaged, is eliminated. For this purpose, the contacts 28 are mounted above the magnetic core 56 of the relay E, with the contacts initially flexed, so that they will remain tightly in engagement. The stationary contact 29 is mounted on a bracket 57, with the arm 30 carried by a magnetic armature 58, pivoted on the core 56, so that the arm 30 rests against contact 28, with the winding 14 deenergized. The armature also carries an upwardly extending rod 59 terminating below an extension 28a of the upper contact 28. Upon energization of the winding 14, upward movement of the armature 58 causes the arm 30 to first leave the contact 29, but the rod 59 does not separate the contacts 28 until the armature 58 has been fully attracted to the dotted line position. Thus, any jarring of the relay E, which might tend to separate the arm 30 from the contact 29 upon slight movement of the armature, will not energize the city box trip coil 25, since the shunt around the trip coil will be maintained by the contacts 28. Furthermore, breakage of a contact 28 will not affect the shunt maintained by the engaged contact 29 and arm 30.

In order to insure that the connected city fire alarm box 24 will be rewound after energization of the trip coil 25 by the relay E, provision is made for locking up this relay. The contacts 15, which are included in the main supervisory circuit in series with the winding 14, are mounted above the contacts 28, with a connection 60 of insulating material between the contact extensions 28a and 15a. Consequently, when upward movement of the armature 58 causes the rod 59 to engage the contact extension 28a, the contacts 15 will be separated at the same time as the contacts 28, thereby opening the circuit of the winding 14.

In order to prevent the armature 58 from dropping back, a latch 61, pivoted at 62, provides an arm 61a, normally resting against the end of the armature 58, when the latter occupies its lower position. When the armature 58 is raised to the dotted line position, in response to energization of the winding 14, the latch arm 61a swings to the left to engage its end under the extremity of the armature 58. Consequently, the armature 58 will be mechanically locked in its attracted position, with the contacts 15 open, even though the winding 14 is then deenergized.

With the armature 58 thus locked up, after operation of the relay E to energize the city box trip coil 25, the trouble signal 34 will continue to operate, due to the break in the main supervisory circuit at the contacts 15. It is obvious that this condition will continue to exist, even though the actuated station S, which initially caused en-

ergization of the relay E, has been restored to normal condition by replacing the broken glass and closing the door, as will be hereinafter described. Therefore, the continued operation of the trouble signal 34 will call attention to the fact that the relay E is still latched up, and that the connected city box should be rewound. In order to unlatch the relay E, it is only necessary to turn the latch lever 61, so as to disengage the arm 61a from the end of the armature 58. For this purpose, a normally retracted plunger 63 is provided, which terminates beneath the end of a second latch lever arm 61b that occupies a substantially horizontal position, as shown in dotted lines, when the armature 58 is latched up.

It is to be noted that the conductors 27 leading to the relay E are the only connection between the city box 24 and the interior alarm system, so that the city box connection is not really a part of the system. Furthermore, if desired, the relay E can be mounted adjacent to the box 24, as indicated diagrammatically in Fig. 5, with leads 64 extending outside to the relay under complete supervision. With such a mounting, unlatching of the relay E, in response to continued operation of the trouble signal 34, is accompanied by rewinding of the tripped box 24.

Should it be desired to actuate a station S to hold a fire drill, provision is made for operation of the interior alarm system, without energizing the trip coil 25 of the box 24 of the city system. For this purpose, each station box can be operated by a suitable key, in possession of a person in authority, with the operation of the key at a station S serving to render the cam device 22 ineffective to open the control contacts 21. In Fig. 3, a key K is shown, diagrammatically, as having been operated so as to prevent turning of the cam device 22, so that subsequent operation of the dispatching mechanism in the usual manner, has no effect on the contacts 21, and the city box trip coil 25 remains shunted out during the operation of the signals 13 of the interior system, for the purpose of a fire drill. With the contacts 21 thus held closed, successive energizations of the main contactor A have no effect on the winding 14 of the trip coil relay, since the previously traced energizing circuit for the winding 14 remains open between the contact 49 and the arm 48 of the then energized city box control relay C. When the key K is withdrawn from the dispatching mechanism at the actuated station, provision is made for holding the contacts 21 closed until the station is restored to its original condition, after the sending of a predetermined number of rounds of code signals has been completed. A dispatching mechanism capable of automatically functioning in the above indicated manner, is disclosed in the co-pending application of John H. Wheelock and Ferdinand F. Humphreys, Serial No. 177,284 filed November 30, 1937, and the essential elements of this mechanism will next be pointed out with reference to Figs. 6 to 9, inclusive.

Referring now to Figs. 6 and 7, one form of dispatching mechanism for use in a system embodying the invention, is mounted in a box 65 having a front 65a, on which a door 66 is hinged. The door 66 provides an opening 67 normally covered by a glass 68, which is broken in order to permit opening of the door, in response to operation of a latch mechanism, hereinafter described. When the door 66 has been opened, the mechanism is adapted to be actuated by a hand lever 69, accessible from the front of the box, as

shown in Fig. 9. The lever 69 is mounted on a shaft 70, and turning of the lever in the direction of the arrow in Fig. 6, causes a toothed sector 71 to turn a pinion 72, mounted on a shaft 73. This shaft 73 is connected to a spring 74, shown in dotted lines in Fig. 7, and turning of the lever 69 causes the spring to be wound. Consequently, upon release of the lever 69, the tension of the wound spring 74 actuates the dispatching mechanism, to cause rotation of a shaft 75, driven from the shaft 73 through suitable gearing 76.

The code wheel 19 of a station S is mounted on the shaft 75, and the ratio of the gearing 76 is such that the code wheel 19 makes several complete revolutions, in response to actuation of the lever 69 to wind the spring 74, by turning the shaft 73 through a portion of one revolution. The projections 19a on the code wheel, are adapted to engage the operating portion 77a of a lever 77 so as to open and close the contacts 18, shown in dotted lines, in accordance with the code sequence, whereby to cause operation of the signals 13 in the manner previously described.

The cam device 22, previously described as normally maintaining a pair of contacts 21 in engagement, consists of a pair of similar cams 78 and 79, mounted one behind the other on the spring shaft 73. While the cams are normally free to turn on the shaft 73, there is sufficient friction between these cams to cause them to turn in unison, unless separately restrained, as will be later described. The inner contact 21 provides an operating finger 80, which is sufficiently wide so as to extend over both cams 78 and 79, and consequently, the contacts 21 are maintained in closed position as long as either of the two cams 78 or 79 is in the position of Fig. 6.

The outer cam 78 provides an arm 81, having an extension 81a projecting into the plane of movement of a plate 82 carried by a plunger 83 adapted to be actuated through a mechanism hereinafter described, under the control of the key K, previously referred to. It is sufficient to state at this point that by means of the key K, the plate 82 can be moved to the position of Fig. 8, so as to prevent the cam 78 from turning with the cam 79, in which position the cam 78 maintains the contacts 21 closed, irrespective of the position of the other cam 79.

The inner cam 79 provides an arm 84, which extends under the arm 81 and provides a projection 84a extending into the path of movement of the code projections 19a on the code wheel 19, see Fig. 7. The inner cam 79 also provides an extension 85, which terminates adjacent a depression 86 in a detent spring 87. When the cam 79 is turned by engagement of a code projection 19a with its arm 84, the extension 85 is snapped into the depression 86 of the spring 87, to yieldingly maintain the cam 79 in a position in which it will permit opening of the contacts 21.

The inner cam 79 also carries a pin 88 extending into the path of movement of a transverse pin 89 carried by the spring shaft 73. The relation between the pins 88 and 89 is such that as the shaft 73 returns to its normal position, after functioning of the dispatching mechanism, the pin 89 engages the pin 88 and restores the inner cam 79 to the position of Fig. 6, which movement disengages the cam extension 85 from the depression 86 of the detent spring 87. This restoring movement also returns the cam 78 to the position of Fig. 6, in alignment with the cam 79,

by reason of the tendency of the cams 78 and 79 to move in unison.

A third cam 90 is secured to the outer end of the shaft 73, and provides an annular flange 91, having a notch 92 in the rim thereof. With the parts occupying the normal non-operating position of Fig. 6, the notch 92 is in alinement with an extension 93 of the plate 82. The extension 93 is of such width as to pass through the notch 92 of the rim cam 90, when the plate 82 is shifted to the left, as shown in Fig. 8. In either position of the plate 82, however, the flange 91 can turn with the shaft 73, so that the plate 82 cannot be shifted during operation of the dispatching mechanism. The plate 82 and its associated plunger 83 is normally maintained in the position of Fig. 6 by a spring 94, in which position a notch 95 at one end of the plate is opposite to the bent-over end 86a of a latch finger 96. A second notch 97 is also provided by the plate 82, and the latch finger 96 is also adapted to co-operate with this notch, as shown in Fig. 8.

A spring 98 normally urges the latch finger 96 in the direction of the plate 82, but with the door 66 closed, as shown in Fig. 6, a lug 99, projecting inwardly from the door, bears on a projection 96b of the latch 96, so as to maintain the end 96a of the latch out of engagement with the plate notch 95. Upon opening of the door 66, withdrawal of the lug 99 permits the spring 98 to move the latch 96 into engagement with one or the other of the two plate notches 95 or 97, in accordance with the position of the plate when the door is opened.

The plate operating plunger 83 is surrounded at one end by a sleeve cam 100, turnable in a tubular housing 101, in which the plunger 83 is longitudinally movable. The cam 100 provides a helical face 102, the base of which is engaged by a pin 103, carried by the plunger, so that turning of the cam 100 will shift the plunger 83 and plate 82 to the position of Fig. 8, wherein a surface 82a of the plate bears on the extension 81a of the arm 81 of the cam 78.

The sleeve cam 100 also provides a transverse groove 104, which, with the door 66 closed, is engaged by a tongue 105 provided at the end of a shaft 106, forming part of the door latch mechanism. The shaft 106 is turnable in an opening 107 extending through the door 66, and its outer end provides a second tongue 108, of such form as to be received in a notch 109 provided at the end of the key K, shown adjacent to door, in Fig. 6. The key also provides a pin 110, adapted to pass through notches 111 formed at the entrance to the opening 107, see Fig. 9. Passage of the pin 110 through the notches 111, insures registration of the outer shaft tongue 108 with the key notch 109, when the key is inserted, in order to operate the sleeve cam 100 and the door latching mechanism, which will next be described.

In Fig. 9, the door 66 is shown on a reduced scale, and is provided with a latch mechanism of the type shown in Ebert Patent No. 1,990,727, dated February 12, 1935. The latch mechanism consists of an arm 112, shown in dotted lines behind the glass 68, with one end of the arm engaged behind a head 113a formed at the end of a stud 113 projecting from the front of the box, as shown in Fig. 8. The arm 112 is loosely pivoted at 114, and its opposite end bears on the conical head 115 of a plunger 116 that is pressed by a spring 117 against the glass 68. A spring 118 tends to hold the latch arm 112 in engagement with the plunger head 115, in which posi-

tion the opposite end engages behind the stud head 113a, to hold the door 66 closed.

When it is desired to operate the box for the purpose of sending an alarm, the glass 68 is broken, whereupon the spring 117 forces the plunger 116 outwardly, into the space previously occupied by the glass. The cone-shaped plunger head 115 is thereupon withdrawn from engagement with the latch arm 112, thereby permitting the spring 118 to turn the arm in a counter-clockwise direction, and disengage its opposite end from the stud 113. The door 66 may then be swung open, to give access to the handle 69, which is then pulled down and released. It is to be noted that opening of the door 66 withdraws the lug 99 from the latch finger 96, thereby permitting the spring 98 to move the end 96a of the finger 96 into the notch 95 of the plate 82. This insures that the plate 82 cannot be moved during the operation of the mechanism for the purpose of sending an alarm throughout the system, and at the same time tripping the associated city box.

When the handle 69 is pulled down, the resulting turning of the shaft 73 as the spring is wound, separates the shaft pin 89 from the cam pin 88. As soon as the wound spring shaft 73 is released, the code wheel starts to turn, and the first code projection 19a turns the lever 77 to open the station coding contacts 18. The first code projection 19a also turns the arm 84 of the inner cam 79, so as to move the cam extension 85 into the depression 86 of the detent spring 87, so that both cams 78 and 79 are, in effect, locked in the dotted line position of Fig. 6, with the contacts 21 open, during the remainder of the operation of the dispatching mechanism. The resulting energization of contactor A, accompanied by deenergization of relays C and D, causes the city box to be tripped almost simultaneously with operation of the signals 13. As the dispatching mechanism runs down, following the sending of a number of code impulses by the signals 13, the pin 89 on shaft 73 engages the pin 88 on the cam 79, and thereby restores both cams to the position of Fig. 6, wherein the contacts 21 are maintained in engagement by the finger 80.

Should it be desired to operate a station S for the purpose of a fire drill, the key K is inserted in the opening 107, with its notch 109 engaging the tongue 108 of the latch shaft 106. The key K is then turned through an angle of approximately 110°, which has the effect of first locking the plate 82 in the position of Fig. 8, and then turning the latch arm 112 so as to permit the door 66 to be opened. The first result is obtained when the helical face 102 of the sleeve cam 100, engages the plunger pin 103, thereby shifting the plunger 83 and its plate 82 to the left, into the position of Fig. 8. In this position of the plate 82, it is impossible for the cam 78 to be turned, due to the engagement of the extension 81a on its arm 81 with the plate face 82a. Further turning of the shaft 106 causes a cam projection 119 thereon to engage the latch arm 112 and shift the whole arm about the plunger 116 as a pivot, so as to disengage the opposite end of the arm from the latch stud 113. The door may now be opened and the handle 69 operated, in order to cause the sounding of an alarm throughout the system, without, however, having any effect on the city box trip coil 25, due to the fact that the cam 78 holds the contacts 21 closed, even

though cam 79 has been moved away from finger 80.

The key K may then be withdrawn, after first turning it back so as to restore the sleeve cam 100 to its initial position. This, however, has no effect on the plunger 83, since the plate 82 is then locked by the latch finger 96, in the position of Fig. 8. In this position of the plate 82, it is also to be noted that the extension 93 is then positioned inside the flange 91 of the cam 90, due to its passage through the notch 92. Therefore, as soon as the shaft 73 is turned by operation of the handle 69, the plate 82 is locked against further movement, throughout the operation of the mechanism.

The above described cooperation between the plate extension 93 and the cam 90, permits the door 66 to be closed and latched, after withdrawal of the key, so that the person who operated the box can go to another location, in order to watch the fire drill. With the plate 82 locked by the rim cam 90, the withdrawal of latch finger 96 by the lug 99, when the door is closed, has no effect on the plate 82. That is to say, the spring 94 is ineffective to return the plate 82 to its initial position, until after the mechanism has run down, and the extension 93 is again in alignment with the notch 92 of the flange 91.

We claim:

1. In an electric signalling system, the combination with transmitting stations including normally closed contacts movable upon actuation of a station, signals, a trip coil for a sending station forming part of an independent system, a relay for energizing said trip coil, a main controller having a winding in a closed supervisory circuit, including said signals and trip coil energizing relay, energizing circuits for said signals, including normally open contacts operable by said controller, with the flow of supervisory current through said controller winding being insufficient to cause closure of its contacts, or to operate said signals or said trip coil energizing relay, of additional normally closed contacts at each transmitting station, and means responsive to the opening of both sets of contacts upon normal actuation of a station to increase the energization of said controller winding and cause closure of said signal operating circuits, and to cause completion of a separate circuit to operate said trip coil energizing relay.

2. In an electric signalling system, the combination with transmitting stations including normally closed contacts movable upon actuation of a station, signals, a trip coil for a sending station forming part of an independent system, a relay for energizing said trip coil, a main controller having a winding in a closed supervisory circuit including said signals and trip coil energizing relay, energizing circuits for said signals, including normally open contacts operable by said controller, with the flow of supervisory current through said controller winding being insufficient to cause closure of its contacts or to operate said signals, or said trip coil energizing relay, of means responsive to the opening of the contacts at any station to increase the energization of said controller winding and cause closure of said signal operating circuits, additional normally closed contacts at each station normally opened with said first-named contacts to cause operation of said trip coil energizing relay, and means at each station to prevent

opening of said second-named contacts with said first-named contacts.

3. In an electric signalling system, the combination with transmitting stations, each providing independent sets of normally closed contacts, signals, a trip coil for the sending station of a separate system, a relay for energizing said trip coil, and a circuit controller for operating said signals, of means responsive to the actuation of a station to open one set of contacts to cause energization of said controller and operation of said signals, other means normally responsive to actuation of a station to open the other set of station contacts and cause operation of said trip coil energizing relay, and means for selectively preventing the opening of said last-named contacts upon actuation of a station.

4. In an electric signalling system, the combination with transmitting stations, each providing independent sets of normally closed contacts, signals, a trip coil for the sending station of a separate system, a relay for energizing said trip coil, and a circuit controller for operating said signals, of means responsive to the actuation of a station to open one set of contacts to cause energization of said controller and operation of said signals, other means normally responsive to actuation of a station to open the other set of station contacts and cause operation of said trip coil energizing relay and key-operated means to permit actuation of a station without opening of said last-named contacts.

5. In an electric signalling system, the combination with transmitting stations each providing independent sets of normally closed contacts, signals, a trip coil for the sending station of a separate system, a relay for energizing said trip coil, and a main controller having a winding in a closed supervisory circuit including said signals and trip coil energizing relay, with the flow of supervisory current insufficient to cause operation of said signals, or of said trip coil energizing relay, of means responsive to the actuation of a station to open one set of contacts to increase the energization of said controller winding and cause operation of said signals, other means normally responsive to actuation of a station to open the other set of station contacts and cause operation of said trip coil energizing relay, and means for selectively preventing the opening of said last-named contacts upon actuation of a station.

6. In an electric signalling system, the combination with transmitting stations each providing independent sets of normally closed contacts, signals, a trip coil for the sending station of a separate system, a relay for energizing said trip coil, and a main controller having a winding in a closed supervisory circuit including said signals and trip coil energizing relay, with the flow of supervisory current insufficient to cause operation of said signals, or of said trip coil energizing relay, of means responsive to the actuation of a station to open one set of contacts to increase the energization of said controller winding and cause operation of said signals, other means normally responsive to actuation of a station to open the other set of station contacts and cause operation of said trip coil energizing relay, and key-operated means for locking said last-named contacts against opening upon actuation of a station.
